UNITED STATES PATENT OFFICE.

FRANK H. STOLP AND CHRISTOPHER WRIGHT, OF CHICAGO, ILLINOIS,
ASSIGNORS TO LONG MANUFACTURING COMPANY, OF CHICAGO,
ILLINOIS, A CORPORATION.

MACHINE FOR MAKING RADIATOR-TUBES.

No. 817,939.

Specification of Letters Patent.

Patented April 17, 1906.

Application filed June 27, 1904. Serial No. 214,875.

To all whom it may concern:

Be it known that we, FRANK H. STOLP and CHRISTOPHER WRIGHT, citizens of the United States, residing at Chicago, in the county of Cook and State of Illinois, have invented certain new and useful Improvements in Machines for Making Radiator-Tubes, &c., of which the following is a specification.

The present invention relates more particularly to machines for making that class of radiator-tubes which have extended radiating-surfaces made of a crimped or corrugated strip or ribbon of thin sheet metal wound spirally around the tube proper to provide a helical flange having crimps or corrugations which are of gradually-decreasing depth from the surface of the tube outward. A machine for making radiator-tubes of this type is shown and described in an application of Frank H. Stolp, 20 one of the parties to this application, filed April 11, 1903, Serial No. 152,208.

One of the objects of the present invention is to improve the machine with respect to the means for revolving the crimping-rolls and mandrel and for moving the mandrel endwise.

Another object of the invention is to provide the machine with means for soldering the strip to the tube as the winding proceeds.

To these ends the invention consists in the features of novelty that are hereinafter described with reference to the accompanying drawings, which are made a part hereof, and in which—

Figure 1 is a plan view of a machine embodying the invention, intermediate portions of some of the parts being broken away to indicate indefiniteness of length and the portions above the line 1 1, Fig. 2, being omitted. Fig. 2 is a front elevation of the principal parts of the machine, including the crimping, winding, and soldering mechanism. Fig. 3 is an end elevation of the machine viewed from the right-hand side of Fig. 2. Fig. 4 is a vertical section on the line 4 4, Fig. 1, looking in the direction of the arrow. Fig. 4^a is a section on the line 4^a, Fig. 4, looking in the direction of the arrow. Fig. 5 is an elevation showing a portion of the machine modified to adapt it for making tubing.

The frame of the machine may be of any construction that will meet the requirements.

A represents a spool on which a strip B of

thin sheet metal is wound and from which said strip is unwound by the action of the 55 crimping-rolls C, between which it passes. On its way to the crimping-rolls the strip runs through a bath of some suitable flux contained in a receptacle D, being guided into and out of the flux by suitably disposed rolls 60 or antifriction-wheels d. The crimping-rolls revolve toward each other and have intermeshing flutes or corrugations by which the strip is crimped or corrugated transversely, as shown at 65 b. After being crimped the strip passes through a suitable guide E and thence to a mandrel F, to which at the start the end of the strip is secured, so that as the mandrel is revolved and moved endwise, as hereinafter described, the crimped strip will be wound 70 thereon edgewise and in a spiral course in the manner described in the application aforesaid.

In making radiator-tubes we prefer to wind the crimped strip directly on the tube proper, 75 or, in other words, make the tube do duty as a mandrel, so that the work is completed at one operation. This arrangement is shown in the drawings, the tubular mandrel being passed through a suitable support G and its 80 end being secured to a chuck H, which is mounted upon a carriage I. To the spindle of the chuck is secured a pinion h, meshing with an idler K, which latter meshes with a gear-wheel L, splined to a shaft M, so as to be 85 incapable of rotating relatively to the shaft, but capable of sliding lengthwise of the shaft. By this means the chuck H, and with it the mandrel F, is rotated.

The gear-wheel L has a tubular shaft, as 90 shown in Fig. 4^a, which carries a pinion N, meshing with a gear-wheel O, the shaft of which carries a beveled pinion P, meshing with a beveled gear-wheel Q, the shaft of which carries a pinion R, meshing with a rack 95 S, carried by a stationary rail T, which constitutes the support for the carriage. The carriage I has appropriate bearings for the shafts of all of the gear-wheels and is slidably mounted upon the rail T, so that as the pinion R is rotated the carriage will be moved along, and thus endwise movement is given the chuck H and mandrel F. The rail T is supported at its ends by portions t of the frame, so as to be incapable of any movement 100 either rotary or endwise, while the shaft M is 125

journaled at its ends in boxes *m*, so that it is capable of rotary but incapable of endwise movement, the endwise movement being prevented by the shoulders, resulting from the reduced portions of the shaft (indicated by dotted lines in Fig. 1) abutting against the boxes *m*. The end of the shaft adjacent to the crimping - rolls carries a beveled gear-wheel *m'*, which meshes with a corresponding wheel *c*, carried by the shaft of one of the crimping-rolls, whereby rotary movement is imparted to it, rotary movement being imparted to the other crimping-roll through the medium of their intermeshing teeth. At its end remote from the crimping - rolls it carries a pinion *U*, which meshes with an idler *U'*, which in turn meshes with a gear-wheel *U''*, carried by a shaft *u*, having a crank-handle *u'* located within convenient reach of the operator as he stands at the crimping and soldering end of the machine. The solder is applied in the form of a strand or wire *V*, which is wound upon the tube spirally, and between the convolutions of the helical flange as the winding of the latter proceeds. This strand of solder is drawn from a reel or spool *W* and on its way to the tube passes through a bath of flux contained in a receptacle *X*, the strand being guided into and out of the receptacle by suitably - disposed antifriction - rolls *z*. When wound and as the winding proceeds, it is heated to melt it, the heat being preferably produced by a gas flame the burner *Y* of which is located below the mandrel in the vicinity of the winding-point, the burner being parallel with the mandrel and sufficiently long to insure the thorough melting of the solder. The melting of the solder does not, of course, take place instantly, some time being required for it to absorb the heat necessary to fuse it, so that for a greater or less distance from the point at which the strand of solder has its initial contact with the mandrel the strand will remain intact between the convolutions of the crimped flange, as shown in Fig. 2. It will, however, be thoroughly fused before passing from the flame. It is found in practice that the solder when melted flows readily into the joint and thoroughly and firmly secures the flange to the tube. This method of soldering forms the subject of another application of even date herewith, bearing Serial No. 214,374. It has many advantages over dipping the entire tube in a solder-bath, and among these may be mentioned the saving of solder, the saving of handling, and the neatness with which the work is done.

The foregoing description has been confined to a machine embodying the invention and adapted particularly for soldering a spiral flange onto a tube; but we desire to have it understood that the invention in its broadest aspect is applicable to other uses,

and in Fig. 5 we have shown a modification of the machine adapted for soldering a spiral joint formed by winding a flat strip of metal *B'* spirally upon a mandrel *F'*, so that the edges of adjacent convolutions come together. We believe ourselves to be the first to provide a soldering - machine in which a continuous strand of unfused solder is wound alone or in proximity to a spiral joint and in which heat is applied during the process of winding to melt and cause it to flow into and close the joint. This is particularly true when the joint is between a tube and a spiral flange thereon. In Fig. 5 only a fragment of the machine is shown; but it may be considered that excepting as there shown the machine is constructed as shown in the other figures of the drawings.

The term "chuck" as used in this specification is intended to comprehend any means or device by which the mandrel may be revolved and is compelled to partake of the movement of the carriage.

What we claim as new, and desire to secure by Letters Patent, is—

1. In a machine of the class described, the combination of a shaft, means for holding it against endwise movement, means for revolving it, a carriage movable in directions parallel with the shaft, a chuck mounted upon the carriage, said chuck being located at the side of the shaft, and with its axis parallel therewith and having means for holding a mandrel in a position parallel with the shaft, means operated by movement derived from the shaft for moving the carriage and for revolving the chuck, and means for feeding a strip to the mandrel whereby it is wound spirally thereon, substantially as described.

2. In a machine of the class described, the combination of a shaft, means for holding it against endwise movement, means for revolving it, a carriage movable in directions parallel with the shaft, a chuck mounted upon the carriage, said chuck being located at the side of the shaft and with its axis parallel therewith and having means for holding a mandrel in a position parallel with the shaft, a stationary rack, a pinion mounted upon the shaft and engaging said rack, means mounted upon the carriage and deriving its movement from the shaft for revolving the pinion and the chuck, and means for feeding a strip to the mandrel whereby it is wound spirally thereon, substantially as described.

3. In a machine of the class described the combination of a shaft, means for holding it against endwise movement, means for revolving it, a carriage movable in directions parallel with the shaft, a support parallel with the shaft, upon which the carriage is mounted, a toothed rack on the support, a pinion mounted upon the carriage and engaging said rack, a chuck mounted upon the

carriage, said chuck being located at the side of the shaft and with its axis parallel therewith and having means for holding a mandrel in a position parallel with the shaft, a train of gear-wheels mounted upon the carriage and deriving their movement from the shaft for revolving the pinion and chuck and means for feeding a strip to the mandrel whereby it is wound spirally thereon, substantially as described.

4. In a machine of the class described, the combination of a shaft, means for holding it against endwise movement, means for revolving it, a carriage movable in directions parallel with the shaft, a chuck mounted upon the carriage, said chuck being located at the side of the shaft and with its axis parallel therewith and having means for holding a mandrel in a position parallel with the shaft, means deriving its movement from the shaft for moving the carriage and revolving the mandrel, a pair of crimping-rolls for crimping a strip and means deriving movement from the shaft for revolving said rolls, substantially as described.

5. In a machine of the class described the combination of means for supporting and revolving an object having a spiral joint to be soldered, means for winding a strand of solder in proximity to said joint, and means for melting the solder during the process of winding, substantially as described.

6. In a machine of the class described, the combination of means for revolving a mandrel, means for feeding a strip thereto, whereby a spiral joint is formed, means for winding a strand of solder in proximity to the joint, and means for melting the solder during the process of winding, substantially as described.

7. In a machine of the class described, the combination of means for revolving a mandrel and moving it endwise, means for feeding a strip thereto whereby it is wound spirally thereon and a spiral joint formed, means for winding a strand of solder in proximity to said joint, and means for melting the solder during the process of winding, substantially as described.

8. In a machine of the class described, the combination of means for revolving a mandrel and moving it endwise, means for feeding a strip thereto whereby it is wound spirally thereon and a spiral joint formed, means for feeding a strand of solder in proximity to the joint during the process of winding said strip upon the mandrel whereby the strand of solder also is wound, means for applying flux to the joint and means for melting the solder during the process of winding, substantially as described.

9. In a machine of the class described, the combination of means for revolving a man-

drel, means for feeding a strip thereto whereby it is wound spirally and a spiral joint formed, means for feeding a strand of solder in proximity to the joint as the winding proceeds whereby the strand of solder is wound upon the mandrel, and a gas-burner located in proximity to the mandrel whereby the solder is melted during the process of winding, substantially as described.

10. In a machine of the class described, the combination of means for revolving a mandrel and moving it endwise, means for feeding a strip thereto whereby it is wound spirally thereon and a spiral joint formed, a flux bath through which the strip passes before reaching the mandrel, means for winding a strand of solder in proximity to the joint, and means for melting the solder during the process of winding, substantially as described.

11. In a machine of the class described, the combination of means for revolving a mandrel and moving it endwise, means for feeding a crimped or corrugated strip thereto edgewise, whereby a spiral flange is formed, means for applying a strand of solder in proximity to the joint between the flange and mandrel, and means for melting the solder, substantially as described.

12. In a machine of the class described, the combination of means for revolving an object having a spiral joint, means for simultaneously winding a strand of solder in proximity to the joint and means for melting the solder during the process of winding, substantially as described.

13. In a machine of the class described, the combination of means for revolving a mandrel having a spiral flange, means for winding a strand of solder in proximity to the joint between the flange and the mandrel and means for melting the solder during the process of winding, substantially as described.

14. In a machine of the class described, the combination of means for winding a strip spirally upon a mandrel whereby a spiral flange is formed, means for winding a strand of solder between the convolutions of the spiral flange and means for melting the solder, substantially as described.

15. In a machine of the class described, the combination of means for revolving a mandrel, means for crimping a strip and feeding it to the mandrel whereby it is wound thereon spirally, means for applying a strand of solder in proximity to the joint between the flange and mandrel and means for melting the solder, substantially as described.
